[57] CLAIM

The ornamental design for a driving ram adapter block, as shown and described.

DESCRIPTION

FIG. 1 is a perspective view of a driving ram adapter block, showing our new design;

FIG. 2 is a front elevational view thereof, the driving ram and cables shown in broken lines are for illustrative purposes only and form no part of the claimed design;

FIG. 3 is a top plan view thereof;

FIG. 4 is a front elevational view thereof;

FIG. 5 is a partial fragmentary side elevational view thereof, the opposite side being substantially identical;

FIG. 6 is a bottom plan view thereof.

FIG. 2

FIG. 1

FIG. 3

FIG. 4

FIG. 5

FIG. 6

UNITED STATES PATENT AND TRADEMARK OFFICE
CERTIFICATE OF CORRECTION

PATENT NO. : Des. 313,999

DATED : January 22, 1991

INVENTOR(S) : Gerald G. Conti and Kurt Conti

It is certified that error appears in the above-identified patent and that said Letters Patent is hereby corrected as shown below:

On the title page, item [19] "Conti" should read --Conti et al--; and item [76] Inventors: should read --Gerald G. Conti, 62 Henshaw Ave., Springfield, N.J. 07081 and Kurt Conti, 160 Oakwood Dr., Murray Hill, N.J. 07974--.

Signed and Sealed this
Thirtieth Day of June, 1992

Attest:

DOUGLAS B. COMER

Attesting Officer

Acting Commissioner of Patents and Trademarks
